LEONARD V. FLECHTER, OF NEW YORK, N. Y., ASSIGNEE TO L. V. FLECHTER & COMPANY
A CORPORATION OF NEW YORK.

CARBURETER.

1,202,847.

Specification of Letters Patent. Patented Apr. 29, 1919.

Application filed December 12, 1912, Serial No. 736,272. Renewed May 9, 1918. Serial No. 232,304.

To all whom it may concern:

Be it known that I, LEONARD V. FLECHTER, a citizen of the United States, whose residence and post-office address is 42 West 67th street, city, county, and State of New York, have invented certain new and useful Improvements in Carbureters, of which the following is a specification.

My invention relates to carbureters particularly to carbureters for use on vehicles such as automobiles.

In the construction of carbureters of the above character, the air and liquid fuel are admitted through a tube which is known as a Venturi or carbureting tube having an outwardly flaring portion in which the air expands and vaporizes a spray of liquid which is carried up with the air. Very often it is found that a portion of the fuel which passes out from the mouth of the Venturi tube becomes condensed and runs down into the chamber surrounding the tube. This is liable to cause a flooding of the chamber and thus interfere with the proper operation of the carbureter. In some forms of carbureters also an auxiliary fuel inlet is provided which extends into the chamber adjacent the tube, which inlet supplies additional fuel at the higher engine speeds. This additional fuel so supplied is also liable to partially condense at certain times and to settle in the chamber.

The principal object of this invention is to overcome this difficulty and to this end I form one or more apertures in the Venturi tube, at or below the bottom wall of the chamber into which the tube projects, so as to allow any oil which may condense in the chamber to flow back into the tube and be vaporized therein.

As the aperture so formed will be close to the line of travel of the air from the auxiliary air valve, I take advantage of this circumstance also to increase the vaporizing efficiency of the Venturi tube. To this end I form the apertures in the tube at an angle to a radial line drawn from the axis of the tube. Thus, if a portion of the air admitted through the auxiliary air passage should pass into the tube, it passes into the same in a direction such as to produce a whirling or eddying effect of the air and spray within the tube and tends to vaporize the fuel more thoroughly and to mix the same more intimately with the air. Also the fuel which

passes in through the openings is sprayed into the tube and given the same whirling motion which effectually vaporizes the same.

In the accompanying drawings:

Figure 1 is a longitudinal sectional elevation of a carbureter embodying my invention.

Fig. 2 is a fragmental section taken along line 2—2 of Fig. 1.

The fuel is conducted to the carbureter by a tube connected in a suitable manner such as through a nipple 1 to the float chamber 2 in which the fuel is kept at approximately constant level by a float 3 which operates a lever 4 connected to a needle valve 5, extending into the opening of the nipple and adapted to close the same when the liquid in the float chamber rises to a predetermined level. The spraying nozzle 6 communicates with the float chamber through a passage 7 and is disposed within the usual Venturi or carbureting tube 8 having an outwardly flaring portion 9 in which the air and fuel spray are thoroughly mixed. This flaring portion 9 of the tube extends within a chamber 10 into which an additional supply of air is admitted to the engine past the auxiliary valve 11 which opens automatically to a degree proportional to the suction of the engine corresponding to increased speed of the same.

I will now describe the novel means whereby the fuel which may become condensed is conducted back to the tube and is revaporized therein. Formed in the wall of the portion of the tube which extends into the chamber 10 are a plurality of apertures 12 located at or below the bottom wall of the chamber and spaced about the tube. These apertures are preferably disposed at an angle to a radius drawn from the axis of the tube as clearly indicated in Fig. 2. When any of the fuel condenses above the tube and drops to the bottom of the chamber 10, it immediately flows back into the tube through these apertures 12 and is thus again vaporized therein. The tube is preferably formed with a circumferential shoulder 12^a adjacent to these apertures. This shoulder is disposed below the bottom of the chamber and forms a circumferential groove or channel about the tube communicating with the apertures. This channel assists in guiding the condensed fuel to the apertures in the tube. The apertures also extend preferably

below the level of the chamber so that the bottoms thereof are preferably on a level with or slightly below the bottom of the channel.

- 5 As the air admitted past the auxiliary valve rushes through the passage 10, a portion of it may also pass into the tube through these apertures 12. However, as these apertures extend at an angle to radii 10 drawn thereto, the air in passing into the tube will assume a whirling motion and thus carry with it any of the condensed oil and spray the same into the tube causing it to intimately mix the rest of the mixture in 15 the tube. This whirling motion also assists the proper mixing of the air and fuel drawn in through the spraying nozzle 6 and the main air inlet.

I have illustrated herein an auxiliary fuel 20 inlet consisting of a tube 13 having an enlarged portion 15, forming a nozzle having a pin-hole opening 16 which is always open to the suction of the engine when the throttle valve is open.

25 As the air admitted past the auxiliary air valve rushes past this auxiliary fuel nozzle, it mixes with the fuel sprayed therefrom and passes up to the engine together with the main fuel mixture. However should a 30 portion of this fuel admitted through the nozzle 15 condense in the chamber 10, it will be carried into the tube through the apertures 12 and be again vaporized.

It will be noted that in the construction of 35 carbureter above disclosed, provision is made for all emergencies and it therefore operates satisfactorily under all conditions of running of the engine. The Venturi tube projecting up into the chamber 10 prevents 40 the air admitted past the auxiliary air valve from unduly disturbing the path of travel of the gases of the mixture from the Venturi tube, whereas should any of the fuel vapor condense it may settle and be sprayed 45 back into the tube by the auxiliary air supply. The latter in entering the tube assumes a whirling motion owing to the novel arrangement of the apertures and thus assists in the thorough mixing of the fuel 50 within the tube.

Various changes may be resorted to within the skill of the mechanic without departing from the spirit and scope of this invention as defined in the appended claims.

55 Having thus described my invention, I claim:—

1. A carbureter comprising a carbureting tube, a fuel spraying nozzle therein, a main air inlet to said carbureting tube, a mixing 60 chamber into which the carbureting tube is extended, and an auxiliary air inlet opening into said mixing chamber, said carbureting tube having an aperture at a level to prevent the accumulation of any condensed fuel 65 in said mixing chamber, said aperture ex-

tending at an angle to a radial line drawn from the axis of the tube.

2. A carbureter comprising a fuel spraying nozzle, a main air inlet, a carbureting tube for said fuel and air, an auxiliary air inlet, a chamber with which said latter inlet communicates, the end of the carbureting tube extending within said chamber, an auxiliary fuel nozzle in said chamber positioned between said tube and said auxiliary air inlet, said tube having a plurality of circumferentially spaced apertures and a groove connecting said apertures, the latter adapted to conduct back into the tube any fuel which may have condensed in said chamber.

3. A carbureter comprising a fuel spraying nozzle, a main air inlet, a carbureting tube for said fuel and air, an auxiliary air inlet, a chamber with which said latter inlet communicates, the end of the carbureting tube being screw threaded for insertion through the bottom of said chamber, said tube having an aperture and a circumferential shoulder below the level of the bottom of the chamber forming a peripheral channel outlined by the bottom of the chamber and communicating with said aperture, adapted to conduct back into the tube any fuel which may have condensed in said chamber.

4. A carbureter comprising a fuel spraying nozzle, a main air inlet, a carbureting tube for said fuel and air having a flaring end to the outlet of the bore, an auxiliary air inlet, a chamber with which said latter inlet communicates, the end of the carbureting tube extending within said chamber and having an aperture a portion of which extends below the level of the bottom of the chamber, and a channel adjacent to the tube communicating with the aperture adapted to conduct back into the tube any fuel which may have condensed in said chamber, said spraying nozzle positioned below said aperture for directing the contents of the mixing tube past said aperture and through said flaring end of the mixing tube.

5. A carbureter comprising a fuel spraying nozzle, a main air inlet, a mixing tube for said fuel and air, an auxiliary air inlet, a chamber with which said latter inlet communicates, the end of the mixing tube extending within said chamber, and having a plurality of circumferentially spaced apertures, extending at an angle to a radial line drawn from the axis of the tube and with portions extending below the level of the bottom of the chamber and a circumferential channel communicating with said apertures adapted to conduct back into the tube through the angularly disposed apertures any fuel which may have condensed in said chamber.

6. In a carbureter, a main fuel spraying nozzle, a main air inlet, a carbureting tube

for the air and fuel, an auxiliary air inlet, a chamber into which the air admitted through the auxiliary air inlet passes, the end of said tube projecting into said chamber, an auxiliary fuel nozzle located in said chamber, said tube having an aperture formed therein located adjacent to the bottom of the chamber and adapted to conduct back into the tube any fuel which may have 10 condensed in said chamber.

7. A carbureter comprising a carbureting tube, a fuel spraying nozzle therein, a main air inlet to said carbureting tube, a mixing chamber into which the carbureting tube is 15 extended, and an auxiliary air inlet opening into said mixing chamber, and a secondary fuel nozzle located in said mixing chamber, said carbureting tube having means located below said secondary fuel nozzle to prevent

the accumulation of any condensed fuel in 20 said mixing chamber.

8. A carbureter comprising a carbureting tube, a fuel spraying nozzle therein, a main air inlet to said carbureting tube, a mixing chamber into which the carbureting tube is 25 extended, an auxiliary air inlet opening into said mixing chamber, and a secondary fuel nozzle located in said mixing chamber, said carbureting tube having an aperture at a level to re-convey to said tube for revaporation any fuel which condenses in the mixing chamber. 30

This specification signed and witnessed this 7th day of December, A. D., 1912.

LEONARD V. FLECHTER.
